Sts., Hillbrow, Johannesburg, Union of South Africa

Filed May 23, 1958, Ser. No. 51,060

Term of patent 14 years

(Cl. D81—10)

Fig. 1 is a side elevation of a pressure stove showing my new design with the chamber partially broken away for clarifying configurational details;

Fig. 2 is a top plan view thereof;

Fig. 3 is a top perspective view of the upper chamber, the stove being omitted for convenience of illustration;

Fig. 4 is a bottom perspective view of the upper chamber of Fig. 3; and

Fig. 5 is a bottom plan view of the upper chamber of Fig. 3.

The essential features of my design reside in the portions shown in full lines.

I claim:

The ornamental design for a pressure stove, as shown and described.
